UNITED STATES PATENT OFFICE.

JAMES P. DOVEL, OF BIRMINGHAM, ALABAMA.

HEAT-RECUPERATING PROCESS AND APPARATUS FOR BLAST-FURNACES.

1,316,086.

Specification of Letters Patent. Patented Sept. 16, 1919.

Application filed December 27, 1918. Serial No. 268,536.

To all whom it may concern:

Be it known that I, JAMES P. DOVEL, a citizen of the United States of America, residing at Birmingham, in the county of 5 Jefferson and State of Alabama, have invented certain new and useful Improvements in Heat-Recuperating Processes and Apparatus for Blast-Furnaces, of which the following is a specification.

10 My invention relates to a heat recuperating process and apparatus for blast furnaces, my object being to devise means whereby the equivalent of a closed circuit may be established for the heat units that 15 have heretofore escaped from the furnace stoves through the stack to the end that by an extremely simple and practicable means the temperature of hot blast may be maintained higher without fuel expense than 20 normal or may be maintained at normal temperature by the use of a less number of stoves.

A further object of my invention relates to its use in connection with a stack induced 25 draft wherein an automatic agency is provided to permit the escape from the closed heat circuit of just sufficient heat units to maintain a uniform stack draft, this being accomplished preferably by means of an 30 automatic valve responsive to stack temperatures and adjustable to control the volume of cold air which is shunted through the recuperating agency. By thus maintaining my stack induced draft substantially 35 uniform in the stoves, the volume of air and gas can be so proportioned as to produce perfect combustion and highest efficiency from the gas consumed, this not being possible with the irregular, variable 40 draft which is obtained from stacks under the present practice. The air and gases are not admitted to the stoves under the same conditions, the gas being under pressure and the air not being under pressure, and 45 the same volumes of air and gas are different, and when it is considered that the variable stack induced draft will affect the entering volume of gas and air to an indefinite degree it will be apparent that the stove 50 valves cannot be adjusted to maintain approximately perfect combustion conditions in the stoves. My invention will greatly assist in this respect by eliminating the variable draft and to that extent will simplify 55 the control of the stove valves and improve their operation and stove efficiency.

It will be understood that my invention contemplates various modifications and embodiments of the essential principles and is not intended to be confined in scope to the 60 embodiment illustrated in the accompanying drawings which form a part of this specification, and in which:—

Figure 1 is a view in side elevation of the stoves and stack with the stack flue shown 65 in section and recuperating coils in side elevation.

Fig. 2 is a plan view of the recuperating coils; and

Fig. 3 is a detail view of the automatic 70 valve and its thermostatic regulator.

Similar reference numerals refer to similar parts throughout the drawings.

In the embodiment of my invention illustrated, 1 is the hot main leading from the 75 stoves 2 to the blast furnace, not shown, and 3 is the stack flue having a manifold connection controlled by the valves 4 with the several stoves at one end and at the other end being connected to the stack 5 or equivalent draft agency. This stack flue is provided with an enlarged recuperating chamber 6 at some intermediate point between the stoves and stack and in this chamber is disposed an air heating arrangement of any 85 suitable character such as the coils 7 connected to the header pipes 8 at each end which in turn have connection by pipes 9 with the cold air main 10 to the stoves. Valves 11 and 12 are provided in the pipes 9 90 and between the points of connection of said pipes with the cold air main I interpose a valve fitting 13 having therein as typical of any suitable valve a vertically adjustable gate valve 14, the stem 15 of which is connected to a bell crank 16 pivotally mounted on a standard 17² on the pipe 10 and having its vertically disposed crank arm connected to the free end of a brass bar 17 forming a thermostat, the other end of which is caused 100 to pass slidably through a stuffing box 18 at one side of the stack and to traverse the stack diametrically and be anchored by plates 19 in the opposite wall of the stack. The bell crank is given an adjustable connection to 105 the stem of the valve by providing the bell crank with a yoke end 20 which works between the nuts 21 screwed on the valve stem.

In operation, having determined the desired stack temperature necessary to maintain the proper draft, say 400° Fahrenheit, the adjustable connections for the automatic 110

valve are regulated so as to leave this valve fully open when the stack temperature stands at 400° Fahrenheit, the valves 11 and 12 being kept open, under which conditions the entering cold air will be shunted past the heating coils on its way to the stoves and will therefore not be preheated before reaching the stoves. As the stack temperature rises above the predetermined maximum of say 400° Fahrenheit an expansion of the thermostatic bar results, which in turn produces a gradual closing of the automatic valve in the cold air main, thereby shunting a portion of the cold air through the heating coils, thus preheating the air and reducing the stack temperature. As the stack temperature tends to vary the automatic valve functions to control the volumetric flow of air through the recuperating coils, so proportioning the latter as to extract all surplus heat units from the furnace gases above the predetermined minimum for draft purposes, these heat units are passed back without appreciable loss into the stoves, thus creating a closed circuit for the heat units from which only a predetermined amount is permitted to escape. If an artificial forced draft is employed, the minimum stack temperature may be reduced to the point where the heat units are practically in a closed circuit.

There are many important advantages which flow from this extremely simple and practical idea for the recuperation of heat, such for instance, as the highly desirable condition of a uniform draft, the reduction in the number of stoves by reason of the greater length of time which the stoves can be used due to the preheated condition of the air supplied; the fact the furnace temperatures can be run to abnormal points heretofore considered impractical by reason of the excessive heat losses, known as stack losses; and the reduction in the amount of fuel required for the blast furnace burden by reason of the higher temperatures of the air blast.

In my pending application September 21st, 1915, Serial No. 51,882, I have heretofore proposed to pass the hot gases flowing from blast furnace stoves through boilers to partially recover the waste heat, but it is not possible by such agency to obtain the contemplated closed circuit for the waste heat units, nor to exercise reliable control over the draft, or to modify the functioning of the stoves or the blast furnace practice as it has heretofore prevailed, all of which are made possible by the utilization of the waste heat for preheating the cold air supply to the stove in a shunted circuit, and I desire

to claim such method and the means for practising it broadly and without restrictions to the specific agencies shown.

Having described my invention, what I claim as new and desire to secure by Letters Patent, is:—

1. The herein-described heat recuperating process for blast furnaces, which consists in transferring heat from the waste gases leaving the blast furnace stoves to the cold air blast for the furnace, thereby setting up a closed circuit for the heat units, and withdrawing sufficient heat units from said closed circuit to maintain a substantially uniform temperature in the gases at their point of discharge. 70

2. In combination, blast furnace stoves, a main for the waste gases conducted therefrom, a heat recuperating agency exposed to waste gases, and automatic means responsive to the temperature of the gases leaving said agency to pass a predetermined volume of the cold air supplied to the stoves through said agency. 80

3. In combination, blast furnace stoves, a main for the waste gases conducted therefrom, a heat recuperating agency exposed to waste gases, a cold air main for the stoves, a shunt circuit from said main which includes said agency, valve means to control the volume of air shunted through said agency, and thermostatic means responsive to stack temperature to automatically adjust said valve means. 90

4. In combination, blast furnace stoves, a stack flue leading therefrom, a cold air main for the stoves, a heat recuperating agency in said flue, pipe means to shunt cold air from said main through said agency, a valve in the cold air main between the points of diversion and return of said shunt air circuit, and a thermostat in the stack for automatically adjusting said valve. 100

5. In combination, blast furnace stoves, a stack flue leading therefrom, a cold air main for the stoves, a heat recuperating agency in said flue, pipe means to shunt cold air from said main through said agency, a valve in the cold air main between the points of diversion and return of said shunt air circuit, and a thermostat in the stack for automatically adjusting said valve comprising a metal bar which traverses the stack being anchored thereto at its inner end and connected to the valve at its outer end, substantially as described. 110

In testimony whereof I affix my signature.

JAMES P. DOVEL.
